COMBINED LOUNGE CHAIR AND DUAL LOUDSPEAKER UNIT

Gordon L. Duern, Elmira, Ontario, Canada, assignor to Dominion Electrohome Industries Limited, Kitchener, Ontario, Canada

Filed Apr. 6, 1967, Ser. No. 6,552

Term of patent 14 years

(Cl. D15—11)

FIGURE 1 is a front perspective view of a combined lounge chair and dual loudspeaker unit showing my design;

FIGURE 2 is a rear perspective view thereof; and

FIGURE 3 is a perspective view showing in greater detail one control panel and a part of one arm of the chair.

The dominant features of my design reside in those portions shown in full lines on the drawing.

The chair is symmetrical about a vertical plane passing through the center of the back and the center of the seat of the chair.

I claim:

The ornamental design for a combined lounge chair and dual loudspeaker unit, as shown and described.
